[57] ABSTRACT

A pyrotechnic initiator with an inherent out-of-line safe/arm feature. The initiator is comprised of a solenoid striker, a diaphragm located between a source of gas vapor and the striker, a secondary explosive, and an igniter. The solenoid punctures the diaphragm allowing the contents from the source of gas vapor to pass into an explosive chamber where a voltage from the igniter ignites the gas. The explosion caused thereby initiates the secondary explosive which produces the desired explosive output.

FIG _ 1

FIG _ 2

3. The device recited in claim 1 wherein said means for controlling the flow of the explosive gas is a diaphragm located in the flow path of said storing gas means and a means for piercing said diaphragm.

4. The device recited in claim 3 wherein said piercing means is a striker.

5. The device recited in claim 1 wherein said igniting means comprises a chamber connecting to said second

dary explosive and in operative relationship with said flowing gas and a pyrotechnic initiator in operative contact with said chamber.

6. The device recited in claim 5 wherein said means for igniting said gas is a glow plug.

7. The device recited in claim 1 wherein the device further includes a means for venting said explosive gas.
